UNITED STATES PATENT OFFICE.

FRANCIS F. HAMILTON, OF INDIANAPOLIS, INDIANA.

DESIGN FOR A BOX.

Application filed August 9, 1924. Serial No. 10,431. Term of patent 14 years.

To all whom it may concern:

Be it known that I, FRANCIS F. HAMILTON, a citizen of the United States, residing at Indianapolis, in the county of Marion and State of Indiana, have invented a new and original ornamental Design for a Box, of which the following is a specification, reference being had to the accompanying drawing, forming a part thereof.

The single figure of the drawing is a perspective view of a box embodying my new design, the box being finished in red cedar, and the trimmings being in dull metal.

I claim:

The ornamental design for a box, as shown and described.

FRANCIS F. HAMILTON.
